UNITED STATES PATENT OFFICE.

FREDERICK W. BUTLER AND WILLIAM E. DEMPSEY, OF AKRON, OHIO.

DESIGN FOR AN EARTHEN JAR.

SPECIFICATION forming part of Design No. 25,405, dated April 21, 1896.

Application filed March 14, 1896. Serial No. 583,264. Term of patent 7 years.

To all whom it may concern:

Be it known that we, FREDERICK W. BUTLER and WILLIAM E. DEMPSEY, citizens of the United States, residing at Akron, in the 5 county of Summit and State of Ohio, have invented and produced a new and original Design for Earthen Jars, of which the following is a specification, reference being had to the accompanying drawings, showing a part thereof.

10 The leading feature of our design consists in a raised annular convex surface, the outlines of which when viewed in elevation, as in either of the figures, and particularly Figure 1, will fall entirely within the abrupt terminal lines of the top of the circular or cylindrical body of the jar, the said leading feature being further marked by the band-like formation which crowns the top of the design.

15 A is the said body of the jar, which is cylindrical in its general contour and plain over its entire surface. Projecting from this body

and from within an abrupt shoulder or offset about its top edge is a semidome-shaped or annular swell B of convex exterior and smooth finish and with the slightly-flaring ring or 25 band C gives distinctness and beauty of design to the top of the jar.

The design is completed, as seen in Fig. 2, by perforated ornamental ear 5, lying wholly within the contour of the swell B and against 30 the ring C, nearly flush with the top thereof.

What we claim is—

The design for a jar, substantially as shown and described.

Witness our hands to the foregoing specification this 7th day of March, 1896.

FREDERICK W. BUTLER.
WILLIAM E. DEMPSEY.
